CATALYTICALLY SWEETENING HEATING OILS

Sumner B. Sweetser, Cranford, Stanley O. Bronson II, Mountainside, and Robert C. Morbeck, Fanwood, N.J., assignors to Esso Research and Engineering Company, a corporation of Delaware

Application November 20, 1952, Serial No. 321,652

4 Claims. (Cl. 196—28)

The present invention is concerned with an improved process for the production of high quality heating oils. The invention is more particularly directed to a process for the preparation of high quality heating oil blends comprising virgin fractions and cracked fractions as for example, catalytically cracked fractions. In accordance with the present process, a hydrocarbon fraction comprising at least predominantly virgin constituents is sweetened using a suitable catalyst and then preferably blended with heating oil constituents secured from a cracking operation. A further preferred adaptation is to employ a two-stage operation wherein the second stage comprises a caustic-air-sweetening stage.

The present invention is broadly concerned with the production of improved hydrocarbon mixtures known as "heating oils," of the nature employed in various burner systems, as diesel fuels, or as domestic and industrial heating oils. Heating oils may be derived from petroleum by a variety of methods including straight distillation from crude petroleum oil, and thermal or catalytic cracking of various petroleum oil fractions.

Heretofore, in the art, heating oil blends comprised a relatively large proportion of virgin heating oil constituents as compared to cracked heating oil constituents. However, due to the desirability of virgin heating oils as feed stocks to various cracking operations, as for example, a fluid catalytic cracking operation, the blends comprise an increasing proportion of cracked heating oil fractions as compared to virgin stocks. Virgin heating oil fractions are also very desirable as diesel oil products which further decreases their availability for heating oil blends.

It is known in the art that heating oils consisting completely or in part of catalytic cracked stocks are characterized by an undesirable instability giving rise to the formation of sediment. It is also known that when cracked heating oils are blended with conversion sweetened virgin heating oils certain undesirable characteristics are increased due to their incompatibility. As a result, such blended fuel oils tend to cause clogging of filters, orifices, or conduits associated with the burning systems in which they are employed.

It is also known in the art that when a sweetened virgin heating oil is blended with a cracked heating oil, the carbon residue of the blend in many cases exceeds the carbon residue of either the virgin heating oil or the cracked heating oil. The carbon residue value is obtained by distilling a sample of the product, taking 90% overhead and leaving 10% as bottoms. The bottoms are then subjected to the standard Conradson carbon test and the results reported as weight percent of carbon residue on the 10% residual used in the test. This carbon residue is an indication of the extent the blended heating oil will carbonize the burners, particularly a rotary burner in actual use and to some extent determines the burning characteristics and desirability of the fuel.

In order to improve the quality of blended heating oils, various processes have been practiced in the art. It is known in the art to process a virgin heating oil by a caustic wash if the oil be relatively sweet. On the other hand, if the virgin heating oil has a relatively high mercaptan content so as to render it sour, the oil is processed by a doctor treat or an equivalent sweetening operation.

2

On the other hand, light cracked heating oils in many operations merely require a caustic wash. However, the conventional procedure is to secure the cracked heating oil from a relatively severe cracking operation in which case it is necessary to acid treat the cracked heating oil followed by a caustic wash in order to control the carbon residue. This latter operation is not desirable since acid treatment polymerizes many desirable constituents which have to be removed by an expensive rerunning operation resulting in a loss in yield. Furthermore, the sludge is expensive and difficult to handle.

In accordance with the present invention, finished heating oils of a satisfactory carbon residue content are produced by blending catalytically sweetened virgin heating oil constituents with cracked heating oil constituents which preferably have been caustic washed. This process eliminates the further treatment of the cracked stocks that would otherwise be necessary due to the serious carbon residue incompatibility that occurs when blending conversion sweetened virgin heating oil constituents with cracked heating oil constituents.

Heating oil blends which may be processed by the catalytic sweetening operation of the present invention are particularly hydrocarbon mixtures of which more than about 10% preferably from about 15% to 60% by volume consist of stocks derived from cracking operations. More precisely still, the finished blends may be characterized as petroleum fractions containing a proportion of cracked stocks greater than 10%, preferably from about 15% to 60% by volume, and falling within ASTM specification D-396-48T for fuel oils (Grades No. 1 or 2). Inspections of a typical heating oil blend are for example:

Gravity, °API	34.5
Distillation, ASTM:	
Initial, B. P., °F.	363
10% @ °F.	438
50% @ °F.	504
90% @ °F.	583
Final, B. P., °F.	640
40 Flash, °F.	158
Color, Tag Robinson	15
Viscosity, SSU/100° F.	34.7
Pour Point, °F.	0
Sulfur, wt. %	.37
45 Suspended Sediment, mgs./100 ml.	1.0
Carbon residue on 10% residuum, % wt.	.08
Corrosion, 1 hr. @ 212° F.	Pass
Diesel index	48.2
Aniline point, °F.	140

50 The process of the present invention may be more fully understood by reference to the drawing illustrating one embodiment of the same. Referring specifically to the drawing, a crude oil feed stock is introduced into distillation zone 1 by means of line 2. Temperature and pressure conditions in zone 1 are adapted to remove overhead by means of line 3 normally gaseous hydrocarbons and to remove by means of line 4 hydrocarbon constituents boiling in the motor fuel and naphtha boiling ranges. A virgin heating oil fraction is removed from zone 1 by means of line 5 while a gas oil fraction is removed by means of line 6. A residuum fraction comprising the higher boiling constituents is removed as a bottoms by means of line 7. The virgin heating oil fraction removed by means of line 5 may be treated by various processes in order to refine the same. In accordance with the present invention this virgin heating oil fraction is catalytically sweetened, utilizing a suitable catalyst such as molybdenum oxide on alumina or cobalt or molybdate on alumina.

65 70 75 It is understood that distillation zone 1 may comprise any suitable number and arrangement of stages. The

gas oil fraction removed by means of line 6 is passed to cracking zone 30 which may comprise any suitable cracking operation, as for example, a thermal or a catalytic cracking process. However, the present invention is particularly directed toward the production of a high quality virgin-cracked heating oil blend wherein the cracking process comprises a catalytic operation, as for example, a fluid catalytic cracking operation.

A fluid catalytic cracking plant is composed of three sections: cracking, regeneration, and fractionation. The cracking reaction takes place continuously in one reactor at a temperature in the range from about 800° F. to 1050° F. The spent catalyst is removed continuously for regeneration in a separate vessel, from which it is returned to the cracking vessel, which is at a pressure below about 200 lbs., usually below about 50 lbs. per square inch. Continuity of flow of catalyst, as well as of oil is thus accomplished, and the characteristic features of fixed-bed designs involving the intermittent shifting of reactors through cracking, purging, and regeneration cycles are eliminated.

Regenerated catalyst is withdrawn from the regenerator and flows by gravity down a standpipe, wherein a sufficiently high pressure head is built up on the catalyst to allow its injection into the fresh liquid oil stream. The resulting mixture of oil and catalyst flows into the reaction vessel, in which gas velocity is intentionally low, so that a high concentration of catalyst will result. The cracking that takes place results in carbon deposition on the catalyst, requiring regeneration of the catalyst. The cracked product oil vapors are withdrawn from the top of the reactor after passing through cyclone separators to free them of any entrained catalyst particles, while the spent catalyst is withdrawn from the bottom of the reactor and is injected into a stream of undiluted air which carries the catalyst into the regeneration vessel. The products of combustion resulting from the regeneration of the catalyst leave the top of this vessel and pass through a series of cyclones where the bulk of the entrained catalyst is recovered. The regenerated catalyst is withdrawn from the bottom of the vessel to complete its cycle.

The cracked products are removed from cracking zone 30 (overhead from the reactor) by means of line 28 and introduced into a distillation zone 16. Temperature and pressure conditions in zone 16 are adjusted to remove overhead by means of line 17 normally gaseous constituents and to remove by means of line 18 hydrocarbon constituents boiling in the motor fuel boiling range. A fraction boiling above the heating oil boiling range is removed as a bottoms fraction by means of line 19. A fraction boiling in the heating oil boiling range is removed by means of line 20 and in accordance with the present invention may be caustic washed in zone 21. The fresh caustic or other treating agent is introduced by means of line 22 while the spent treating agent is removed by means of line 23. In accordance with the present invention, the caustic washed cracked heating oil is blended with the catalytic sweetened virgin heating oil, produced as hereinafter described.

In accordance with the present invention the virgin heating oil removed by means of line 5 is catalytically sweetened in zone 8. This operation is carried out in the presence of a suitable catalyst such as cobalt molybdate on alumina or molybdenum oxide on alumina. In general, the amount of alumina is in the range from about 85 to 95% by weight. The temperatures utilized in the catalytically sweetened operation are in the range of about 550° to 650° F. Preferred temperatures are in the range from about 575° to 625° F. Satisfactory pressures are in the range from about atmospheric to 400 p. s. i. g., while the preferred pressures are in the range from about 175 to 250 p. s. i. g. The feed rates may vary appreciably depending upon various selected operating conditions, but in general, are of the order of

space velocities of from about 1 to 16 volumes of feed per volume of catalyst per hour. Preferred feed rates are from about 4 to 8 volumes of liquid feed per volume of catalyst per hour.

5 In general, operating conditions are adjusted to secure a liquid phase operation. Under these conditions less heat transfer equipment is required, since there is no need to vaporize the feed and condense the product. Furthermore, in a liquid phase operation, carbonaceous materials formed in the reaction zone are continuously washed off the catalyst.

10 In accordance with one adaptation of the present invention, the catalytically sweetened virgin heating oil fraction is withdrawn from zone 8 by means of line 50 and after caustic washing and other treatment for removal of hydrogen sulfide is blended with the caustic washed, cracked constituents in line 24.

15 While in many instances a satisfactory product can be secured utilizing a single stage, that is, a catalytic sweetening stage on the virgin constituents, in many other instances in order to secure a good odor product, it is desirable to use a second air sweetening stage in conjunction with the catalytic sweetening stage. Under this mode of operation the catalytic sweetening virgin constituents may be passed through to air caustic sweetened zone 40 by means of line 41. It is more desirable to remove the catalytic sweetened stock from zone 8 by means of line 51 and to pass the same to zone 52 wherein hydrogen sulfide is removed. Removal is accomplished 20 preferably by the introduction of steam by means of line 53 and the removal of hydrogen sulfide by means of line 54.

25 The fraction substantially free of hydrogen sulfide is removed from the bottom of the zone 52 by means of line 55 and introduced into zone 56, wherein the same is contacted with a weak caustic solution. The weak caustic solution is introduced into zone 56 by means of line 57 and withdrawn by means of line 58. This caustic solution is preferably a 10 to 20° Bé solution. Approximately 0.1 to 2.0% by volume of caustic is utilized, based upon the oil.

30 The treated oil is then introduced into caustic air sweetening zone 40 wherein the same is contacted with a strong caustic solution, as for example, one having a concentration of from about 45 to 50° Bé. Approximately 1 to 3% by volume of the strong caustic solution is utilized, based upon the oil. Sufficient air is introduced to give good agitation and to provide the necessary oxygen. The time of contact is approximately 15 minutes to 240 minutes.

35 The catalytic sweetened, caustic-air-sweetened virgin fraction is removed from zone 40 by means of line 42 and blended with the cracked constituents introduced by means of line 24.

40 The invention is broadly concerned with the production of a heating oil blend comprising cracked and virgin constituents. In accordance with the present process, the virgin constituents are catalytically sweetened and are preferably thereafter caustic-air-sweetened prior to blending with the cracked constituents.

45 It is of the utmost importance that the feed stock be of a particular character, that is, be substantially virgin constituents. If cracked stocks, per se, are utilized, a marked increase in the carbon residue of the treated oil results. However, the process may be carried out utilizing a certain amount of cracked constituents in conjunction with the virgin constituents. Under these circumstances, the amount of cracked constituents should not exceed about 25% and should preferably be less than 15% by volume, based upon the total feed.

50 During the course of the operation, carbon tends to accumulate on the catalyst. After the efficiency of the catalyst has decreased to a predetermined level, the catalyst may be regenerated by the removal of the carbon, preferably by burning with air.

The process of the present invention may be more fully understood by the following examples illustrating the same:

EXAMPLE 1

A number of operations were carried out wherein a heating oil having the following specifications

Boiling range	° F.	307-554
Mercaptan No. *		91
Sulfur, weight percent		0.68
Carbon residue (10% residuum) weight percent		0.04

* Mercaptan number is defined as mg. of mercaptan sulfur per 100 ml. of sample.

was treated with a catalyst comprising about 10% molybdenum oxide on alumina. The results of these operations are illustrated in the following table.

TABLE I
West Texas light virgin heating oil

Column	A	B	C
Processing Steps:	Feed		
(1) Catalytic Sweetening ¹	No. 91	Yes	Yes
(2) Air-Caustic Sweetening ²	No. 4.5	0.0	
Product Inspections:			
Mercaptan Number	91		
Sulfur, Wt. Percent	0.68	0.57	
Doctor Test	DNP	DNP	Pass.
Carbon Residue, Wt. Percent	0.04	0.00, 0.01	0.03, 0.03
Compatibility with Caustic Washed Catalytic Heating Oil ³ :			
Carbon Residue (10% Residuum), Wt. Percent—Experimental		0.07, 0.08	0.09, 0.11
Calculated from Components		0.05	0.07
Blending Value of Virgin Stock		0.04, 0.06	0.08, 0.12

¹ 8 v./hr./v., 600° F., 200 p. s. i. g.

² 2% 48° Be⁴ caustic, 125° F., required 3 to 4 hours to obtain doctor pass product.

³ 50% concentration in cracked heating oil having a carbon residue of 0.10 wt. percent.

The above results show that although catalytic sweetening reduced the mercaptan number of feed from 91 to 4.5, the product obtained would not pass the doctor test. In other words, it contains some residual mercaptans. However, by giving the catalytically sweetened product a further mild treatment with air and dilute caustic, the mercaptan number was reduced to zero and a doctor pass product was obtained. In obtaining the doctor pass product, there was no marked increase in the value for the carbon residue.

EXAMPLE 2

Other operations were carried out to determine the effect of velocity and temperature. The results of these operations are shown in Table II.

TABLE II

Catalytic sweetening of West Texas light virgin heating oil over MoO_3 on alumina catalyst

EFFECT OF SPACE VELOCITY @ 600° F. AND 200 P. S. I. G.

V.V./Hr.	Feed	1	2	4	6	8
Mercaptan No. mg. S/100 ml.	91	2	2	3	4	5
Sulfur, Wt. Percent	0.67	0.44	0.48	0.51	0.55	0.55
Carbon Residue, Wt. Percent:						
Unblended	0.07	0.01	0.01	0.01	0.01	0.01
Blended ¹	0.07	0.05	0.07	0.07	0.08	0.08

EFFECT OF TEMPERATURE AT 200 P. S. I. G. AND 4 V./V./HR.

Temperature, ° F.	Feed	400	500	600
Mercaptan No.	91	68	45	2
Sulfur, Wt. Percent	0.67	0.60	0.55	0.50
Carbon Residue, Wt. Percent:				
Unblended	0.07	0.07	0.04	0.03
Blended ¹	0.07	0.05	0.05	0.08

¹ Blended in 50-50 proportion with caustic washed cracked heating oil having carbon residue of 0.10 wt. percent.

From the above it is apparent that the mercaptan num-

ber decreases as space velocity decreases. It is also apparent that complete removal of the mercaptans is not obtained even at relatively low space velocities, but that complete removal is secured by subsequent caustic air operation. The carbon residue of the product is materially improved.

EXAMPLE 3

Other operations were conducted to determine the relative effect of sweetening by a hydrofining operation and by a catalytically sweetening operation. The results of these operations are illustrated in Table III.

TABLE III

Comparison of hydrofining and catalytic sweetening of West Texas light virgin heating oil

Column	A	B	C	20 Catalyst	Hydrofining	Catalytic Sweetening	Bauxite Treating
					Molybdenum Oxide on Alumina		
Processing Steps:	Feed						
(1) Catalytic Sweetening ¹	No. 91	Yes	Yes				
(2) Air-Caustic Sweetening ²	No. 4.5	0.0					
Product Inspections:							
Mercaptan Number	91						
Sulfur, Wt. Percent	0.68	0.57					
Doctor Test	DNP	DNP					
Carbon Residue, Wt. Percent	0.04	0.00, 0.01	0.03, 0.03				
Compatibility with Caustic Washed Catalytic Heating Oil ³ :							
Carbon Residue (10% Residuum), Wt. Percent—Experimental		0.07, 0.08	0.09, 0.11				
Calculated from Components		0.05	0.07				
Blending Value of Virgin Stock		0.04, 0.06	0.08, 0.12				

¹ Caustic washed cracked heating oil has carbon residue of 0.09 wt. percent. When same cracked oil was blended 50/50 with the West Texas light virgin heating oil sweetened by PbS/S method, carbon residue was 0.42 wt. percent.

The above results show that although catalytic sweetening gives less sulfur removal than hydrofining, the mercaptans as measured by mercaptan number are substantially eliminated. Furthermore, catalytic sweetening gives a substantial reduction in carbon residue and improves the compatibility of the sweetened stock with caustic washed cracked heating oil. Catalytic sweetening has an economical advantage over hydrofining in that no hydrogen supply or hydrogen recycle is required. Bauxite treating at 1 v./hr./v. was much less effective than catalytic sweetening at 8 v./hr./v. in removing mercaptans and in reducing carbon residue.

EXAMPLE 4

A heating oil containing only cracked components boiling in the range of 330 to 650° F. was catalytically sweetened at 600° and 200 lbs. pressure. The carbon residue was increased by this operation from .13 to .46 weight percent, showing that catalytic sweetening is not effective on heating oils containing only cracked constituents. In a second operation a blend containing 80% of light virgin heating oil and 20% of heavy cracked heating oil was catalytically sweetened at 600° F., 200 lbs. pressure, and a feed rate of 4 v./hr./v. Inspections on the feed and product are shown in the following tabulation:

Column	Feed	Virgin+Cracked Feed	Cat. Sweetened Product
Sulfur, Wt. Percent	0.837		0.717
Mercaptan Number	62		1.5
Carbon Residue (10%), Wt. Percent	0.01		0.04

The above results illustrate that when a virgin feed is blended with relatively small amounts of cracked feeds, catalytic sweetening is effective.

What is claimed is:

1. Improved process for the sweetening of hydrocarbon constituents boiling in the heating oil boiling range which comprises contacting said constituents at a temperature in the range from about 550° to 650° F., and at a pressure in the range from about atmospheric to 400 lbs. p. s. i. g. in the absence of added gases with a catalyst selected from the class consisting of molybdenum oxide on alumina and cobalt molybdate on alumina and thereafter contacting said treated hydrocarbon constituents with caustic and air in a second stage treatment.

2. Process as defined by claim 1 wherein the temperature is in the range from about 575° to 625° F.

3. Process for the preparation of high quality heating oil blends comprising cracked and virgin constituents which comprises contacting said virgin constituents with a catalyst selected from the class of cobalt molybdate on alumina and molybdenum oxide on alumina at a tem- 15

10

perature in the range from about 550° to 650° F., and at a pressure in the range from about atmospheric to 400 lbs. p. s. i. g., withdrawing the virgin constituents from said catalyst and blending the same with cracked constituents boiling in the heating oil boiling range, whereby a low Conradson carbon product is secured.

4. Process as defined by claim 3 wherein said virgin constituents are contacted with air and caustic prior to blending the same with said cracked constituents.
